FAUCET HANDLE

Harold Shames, 5 Agnes Circle, and Sidney J. Shames,
19 Agnes Circle, both of Ardsley, N.Y.

Filed June 12, 1961, Ser. No. 65,571

Term of patent 14 years

(Cl. D91—3)

Fig. 1

Fig. 2

Fig. 3

Fig. 4

Fig. 5

Fig. 6

FIGURE 1 is a perspective view of a faucet handle embodying our new design;

FIGURE 2 is a top plan view thereof;

FIGURE 3 is a side elevational view thereof;

FIGURE 4 is an end elevational view thereof as seen from the left of FIGURE 3;

FIGURE 5 is an end elevational view thereof as seen from the right of FIGURE 3; and

FIGURE 6 is a bottom plan view thereof.

We claim:

The ornamental design for a faucet handle, substantially as shown and described.
